UNITED STATES PATENT OFFICE.

IRVINE MCCOLL, OF GRAND RAPIDS, MICHIGAN.

RECEPTACLE OR PACKAGE.

Application filed August 28, 1922. Serial No. 584,800.

To all whom it may concern:

Be it known that I, IRVINE MCCOLL, a citizen of the United States, residing at Grand Rapids, county of Kent, State of Michigan, have invented certain new and useful Improvements in Receptacles or Packages, of which the following is a specification.

This invention relates to improvements in receptacles or packages. My improvements relate particularly to receptacles or packages for ice cream or similar material which it is desired to keep in proper condition, or for heated materials which it is desired to deliver hot.

The main object of this invention is to provide an improved package of the class described which is effective in retaining the packaged material in either hot or cold condition, as it may be packaged, and at the same time a package which is easily assembled with the contents therein, and disassembled permitting the reuse of the outer container members should it be desired.

A further object is to provide a package having these advantages which is simple and economical in structure.

Objects pertaining to details and economies of the invention will definitely appear from the detailed description to follow.

I accomplish the objects of my invention by the devices and means described in the following specification. The invention is clearly defined and pointed out in the claims.

A structure which is a preferred embodiment of the invention is clearly illustrated in the accompanying drawing forming a part of this specification, in which:

Fig. I is a vertical central section through a package embodying the features of my invention on a line corresponding to line 1—1 of Fig. II.

Fig. II is a horizontal section on a line corresponding to line 2—2 of Fig. I.

Fig. III is a vertical central section of a slightly modified form of my invention.

Fig. IV is a plan view of one of the spacing members.

Fig. V is a plan view of one of the base members in extended form.

In the drawings the sectional views are taken looking in the direction of the little arrows at the ends of the section lines and similar numerals of reference refer to similar parts throughout the several views.

Referring to the drawing, I provide a plurality of receptacles as 1, 2, 3 and 4, preferably of cylindrical form, and comprising cylindrical side walls with flanged bottoms 5 secured thereto. The inner receptacle 1 has an inner bottom 6 spaced from its bottom 5 providing a closed air chamber 7. The receptacles are each provided with an independent cover 8, 9, 10 and 11.

The receptacles are of such size that when arranged one within the other they provide surrounding air chambers 12. The enclosed receptacles are provided with conical flange-like bases 13 which support the enclosed receptacles with their bottoms and side walls in spaced relation, thus providing air chambers surrounding each receptacle. These may be formed of light cardboard-like material, the contents being pressed within the receptacle 1, ice cream for instance, and is prevented from melting for a long period of time, it being very effectively insulated by the surrounding air chambers.

In the modification shown in Figs. III, IV and V the receptacles 14, 15, 16 and 17 are arranged substantially as described, the bottoms 18 being of the same character as the bottoms 5 in the preferred construction. The bases, however, are modified, the bases 19 being in the form of bands which are secured to the lower portions of the receptacles to provide cylindrical flange-like projections. These bases 19 have slots 20 below the planes of the bottoms through which the tongue-like projections 21 on the disks 22 project, these disks being arranged against the under sides of the bottoms with their tongues projecting through the slots thereby supporting each receptacle in an elevated position within its containing receptacle, the tongues or lugs 21 supporting it concentrically therein. The result is substantially the same as that of the embodiment of Figs. I and II.

I have not attempted to illustrate or describe other embodiments or adaptations of my improvements which I contemplate, as I believe the disclosure made will enable those skilled in the art to which my invention relates to embody or adapt the same as may be desired.

Having thus described my invention what I claim as new and desire to secure by Letters Patent is:

1. A package comprising a plurality of

receptacles disposed one within another, the inner receptacle being adapted to receive the material to be packaged and having a double walled bottom providing a bottom air chamber, the enclosed receptacles being provided with conical flange-like bases constituting supporting and spacing members removably supporting the receptacles one within another with their walls in spaced relation, said receptacles being provided with independent covers.

2. A package comprising a plurality of receptacles disposed one within another, the inner receptacle being adapted to receive the contents to be packaged and being provided with double walled bottom providing a bottom air chamber, and supporting and spacing members at the bottoms of the enclosed receptacles removably supporting them one within another in concentric spaced relation providing a plurality of air chambers for the inner receptacle, each receptacle being provided with an independent cover.

25 3. A package comprising receptacles disposed one within another, the inner receptacle being adapted to receive the material to be packaged and having a double walled bottom providing a bottom air chamber, and having a conical flange-like base constituting a supporting and spacing member removably supporting the inner receptacle

within the outer with their walls in spaced relation.

4. A package comprising receptacles disposed one within another, the inner receptacle being adapted to receive the material to be packaged and having a conical flange-like base constituting a supporting and spacing member removably supporting the inner receptacle within the outer with their walls in spaced relation.

5. A package comprising receptacles disposed one within another, the inner receptacle being adapted to receive the contents to be packaged and being provided with double walled bottom providing a bottom air chamber, and with a supporting and spacing member at the bottom removably supporting it in concentric spaced relation with the outer receptacle, each receptacle being provided with an independent cover.

6. A package comprising receptacles disposed one within another, the inner receptacle being adapted to receive the contents to be packaged and being provided with a flange-like supporting member at its bottom removably supporting it in concentric spaced relation within the outer receptacle and providing an air chamber below the enclosed receptacle.

In witness whereof, I have hereunto set my hand and seal.

IRVINE McCOLL. [L. s.]
